DESIGN FOR A COMBINATION DESK UNIT

Ernest H. Reiss, Floral Park, N. Y.

Application June 26, 1947, Serial No. 139,945

Term of patent 14 years

(Cl. D52—7)

To all whom it may concern:

Be it known that I, Ernest H. Reiss, a citizen of the United States of America and resident of Floral Park, county of Nassau, and State of New York, have invented a new, original, and ornamental Design for a Combination Desk Unit, of which the following is a specification, reference being had to the accompanying drawing, forming part thereof, in which

Fig. 1 is a front elevation of a combination desk unit, showing my new design;

Fig. 2 is a side elevation of the same, and

Fig. 3 is a rear elevation of the unit, with the parts thereof in separated position.

I claim:

The ornamental design for a combination desk unit, substantially as shown.

ERNEST H. REISS.
